PREFABRICATED ARTIFICIAL TOOTH AND FACIAL MEMBER

Irving Neustadter, Brooklyn, N. Y., assignor to Precious Metals Research Works, Inc., New York, N. Y., a corporation of New York

Application November 12, 1953, Serial No. 391,507

9 Claims. (Cl. 32—10)

The invention is directed to a prefabricated artificial tooth including a combination of a prefabricated bridge or retaining member and a prefabricated facial tooth color member which is received by the bridge member. The invention also includes the prefabricated facial member which may serve a temporary use only to provide the dentist with a try-in or to serve as the facial carving pattern which after being invested with the metal bridge is extracted and the space remaining acts as the mold for processing the permanent plastic tooth, or may be cemented to the bridge member to form a completely prefabricated tooth.

The invention herein presents certain improvements and advantages over that disclosed in my application for patent SN 329,300 filed January 2, 1953 and now abandoned. This earlier application discloses a prefabricated retaining or bridge member for a tooth which comprises a transverse occlusal portion with an integral semicircular lingual portion extending from the rear edge thereof. The prefabricated bridge member forms the support for the artificial facial member. In this earlier application the facial tooth color portion is individually carved to shape in wax within the bridge member to form a pattern from which the plastic tooth is moulded. This prefabricated retaining or bridge member is used with a prefabricated facial member which fits into and is retained by the bridge member and the dentist as a preliminary step can connect the bridge member in position with wax, affix the prefabricated facial member for inspection after which the bridge members are soldered together. This was impossible heretofore. Also after assembling a bridge or restoration of one or more bridge members, he again inserts a prefabricated facial member into each bridge member and he can examine the bridge as it actually will appear in the mouth and make such changes as he may deem desirable. Heretofore with just the metal part of bridge, it was difficult to visualize the final appearance of the restoration. Heretofore too, the dentist or dental technician shaped each labial or buccal portion from wax to form the pattern, which after investing and subsequently boiling out, provided the mould into which plastic of the correct color was processed, which step required great anatomical knowledge and carving skill.

It is an object of the invention to construct an artificial tooth combination of a prefabricated bridge member and a prefabricated facial tooth color member which will give the dentist both a preview and a try-in of a restoration in the mouth of the patient.

Another object is to construct an artificial tooth combination of a prefabricated bridge member and a prefabricated facial member for insertion in the bridge member to use the prefabricated facial member as the pattern for processing the permanent plastic section of the tooth.

Another object is to construct a completely prefabricated artificial tooth.

2

A still further object is to construct a prefabricated facial member which is insertable into a prefabricated retaining or bridge member to give the dentist both a preview and a try-in of a restoration to actually see the appearance and position of a restoration in the mouth of a patient.

Another object is to construct an insertable prefabricated facial tooth color member which may be inserted preliminarily in order to check a restoration for appearance, position and the like and then can be cemented in position within the bridge or retaining member to form a completely prefabricated artificial tooth.

Other objects of the invention will be more apparent from the following description when taken in connection with the accompanying drawing illustrating preferred forms of the invention in which:

Figure 1 shows a front view of an artificial posterior tooth;

Figure 2 is a side view of the tooth;

Figure 3 is a rear or back view of the tooth;

Figure 4 is a central vertical sectional view taken on line 4—4 of Figure 1;

Figure 5 is a rear view of the facial member;

Figure 6 is a front view of an anterior form of retaining or bridge member;

Figure 7 is a sectional view taken on line 7—7 of Figure 6;

Figure 8 is a side view of the facial tooth color member of an anterior tooth;

Figure 9 is a rear or back view of the facial member for the bridge member of Figures 6 and 7; and

Figure 10 shows a bridge member with a metal saddle secured to the bottom thereof.

The bridge member is formed of metal, usually cast and of gold or formed of plastic to be used as a pattern to be cast in metal by the lost-wax method. A posterior bridge member has a transverse occlusal portion 10 having an occlusal surface 11 corresponding to a natural tooth and an inner surface 12. Integral with the rear or back edge of the occlusal portion is a dependent portion which will be termed a lingual portion 13 of the bridge member including a lingual wall and mesial, distal walls 14 which extend forwardly from the lingual wall.

The mesial, distal and lingual walls form an approximately semicircular continuous wall and the outer surface or lingual, mesial and distal surfaces conform with a natural tooth. Preferably the mesial, distal and the lingual walls extend for a length corresponding to the length of the natural tooth which it will replace. The side walls slope inwardly in conformity with the natural shape of a tooth.

A prefabricated facial tooth color member 17 is received by the bridge or retaining member. It carries the color of the tooth so that it will appear as a natural tooth and forms the greater portion of the restoration or tooth. Its exposed surfaces, including the buccal, mesial and distal surfaces, are shaped to conform to a natural tooth. The upper surface 19 conforms with the inner surface 12 of the occlusal portion of the bridge member and the back surface 20 conforms to the inner wall of the bridge member. A shoulder 21 on the facial member engages or abuts the edges of the bridge member. When assembled together the mesial, distal surfaces of the facial member and bridge member form a continuous tooth surface. Figure 1 shows that the bridge member is completely invisible from the front except for the thin front edge of the occlusal portion.

The front edges of the mesial, distal walls of the bridge member are invisible or practically invisible behind the facial member. The front overhanging portion 22 of

the facial member is free to be seated naturally upon the gum.

Means are provided to retain the facial tooth color member within the bridge member. The retention means may take many forms that shown in Figures 1-5 for a posterior tooth being a pin or projection 23 which extends outwardly from a wall of the bridge member and particularly shown as extending from the inner wall of the lingual portion adjacent to the occlusal portion. A hole 24 in the back of the facial member receives the pin and retains the facial portion within the bridge member.

Figures 6-9 illustrate a prefabricated bridge and facial member for an anterior tooth as well as another form of means for retaining a facial member within the bridge member. The anterior bridge member 27 has a biting surface or an incisal edge 28 and a lingual portion of which merges into a generally semicircular end 29 at the gum. Shoulders 33 of the facial member at the mesial, distal surfaces abut and correspond with the edges 32 of the bridge member. The means for retaining the facial member on the bridge member includes flange or rib means which may include a vertical flange or rib 30 and a horizontal flange or rib 31 extending between the inner side walls of the bridge member, and both being carried by the inner wall of the bridge member. One rib only may be provided; however, since they also give greater rigidity and strength to the bridge member, the ribs particularly illustrated are preferred. The facial tooth color member for an anterior tooth, as shown in Figures 8 and 9, has a recess in the form of a groove in its back surface for each rib to receive the same. A vertical groove 35 receives the vertical rib flange 30 and a horizontal groove 36 receives the horizontal rib or flange 31.

The facial tooth color member may serve as a test part in that when a restoration or frame of one or more bridge members has been made a prefabricated facial member is inserted in each bridge member and the dentist can see the restoration just as it will appear in the mouth and make alterations if that should be deemed desirable. The facial member may be ground to alter its appearance, may be cut off to shorten it, or wax may be added to it if required. The case is then invested with each facial member within the bridge member so that it also serves as a pattern. After investing, the facial member is removed, and a facial of plastic may be molded into each bridge member. When a molded facial is used the retention pin is undercut and the ribs or flanges may have holes drilled therein or undercut for permanent anchorage. Also the prefabricated facial member of the proper color may be cemented into the bridge member and form the permanent facial for the bridge member or tooth.

A metal dental frame of a plurality of bridge members may be made by soldering together the needed number of bridge members of the proper sizes and shapes to conform to the natural teeth which they will replace and soldering them to abutments as described in my earlier application.

The occlusal surface of a posterior tooth and the incisal edge of an anterior tooth constitute biting surfaces of the bridge member. The lingual surface tapers from the incisal edge of the anterior tooth bridge member and becomes approximately semicircular at the gingival of the bridge member. At least a part of the lingual portion of the bridge member is approximately semicircular or the lingual portion of the bridge member at least at the gingival is approximately semicircular.

In Figure 10 is shown a construction in which a metal foil or member, adapted to conform to the tissue bearing surface of the mouth may be soldered to the bottom of the bridge member to form a saddle 39. The saddle alone may carry the retaining means for retaining the facial member within the bridge member if desired. The

saddle forms a part of the bridge member and also gives additional rigidity to the restoration and provides a gold tissue surface when and where the dentist desires it.

The prefabricated bridge member or a plastic pattern 5 from which the bridge member may be cast and prefabricated facial members are made in forms and sizes for all or at least the principal natural teeth, such as upper and lower posteriors and anteriors, although two forms only are particularly illustrated and described herein. Presently about ninety-six different forms and sizes 10 are made. The prefabricated members are sold as articles of commerce. The bridge units may be sold as metal units ready for immediate use as such or as plastic patterns from which metal units may be cast. The 15 facial members are sold ready for temporary or permanent use.

When a permanent facial member is molded within the bridge member it is necessary to provide retaining means. The means for all forms of teeth for retaining the facial 20 member within or on the bridge member comprises therefore at least one projection carried by an inner wall of the bridge member. A corresponding recess is provided in the prefabricated facial member for each projection and receives the same. It is desirable, though not necessary, to provide retaining means when the prefabricated 25 facial member is cemented into the bridge member to form a permanent part of the tooth.

The invention is presented to fill a need for improvements in a prefabricated artificial tooth and facial member. It is understood that various modifications in structure, as well as changes in mode of operation, assembly 30 and manner of use, may and often do occur to those skilled in the art, especially after benefiting from the teachings of an invention. Hence, it will be understood that this disclosure is illustrative of preferred means of 35 embodying the invention in useful form by explaining the construction, operation and advantages thereof.

What is claimed is:

1. A prefabricated tooth comprising a prefabricated 40 bridge member having a biting portion of the form of the tooth it is to replace, a lingual portion integral with the biting portion, a mesial portion and a distal portion integral with at least the lingual portion and approximately semicircular in form at least at the gingival, the lingual, mesial and distal portions having lingual, mesial and distal surfaces conforming to a natural tooth at least the lingual, mesial and distal portions of the bridge member having inner surfaces, the lingual, mesial and distal 45 portions having substantially uniform wall thickness; and a prefabricated facial member having labial or buccal, mesial and distal faces conforming to a natural tooth, and the back face and sides conforming to the inner surfaces of the bridge member; a saddle extending across the bottom of the lingual, mesial and distal faces, and means 50 carried by the saddle of the prefabricated bridge member and the prefabricated facial member for retaining the members together.

2. A prefabricated tooth comprising a prefabricated 60 dental bridge member having a horizontal occlusal portion, the occlusal portion having an upper surface of the form of the occlusal surface of a tooth and an inner surface, a lingual portion integral with the rear edge of the occlusal portion, a mesial portion and a distal portion integral with the occlusal portion and the lingual portion 65 and approximately semicircular in form, each portion having an inner surface; a facial member having buccal and mesial, distal surfaces conforming to a natural tooth, the upper surface of the facial member conforming to the form of the inner surface of the occlusal portion of the bridge member, and the rear surface and sides conforming to the inner surfaces of the lingual mesial and distal portions of the bridge member, and means carried by the bridge member for retaining the facial member within 70 the bridge member.

3. A prefabricated tooth as in claim 2 in which the semicircular portion has a length corresponding with the lingual and mesial, distal length of a natural tooth above the gum.

4. A prefabricated tooth as in claim 2 in which the retaining means is carried by a saddle secured to the bottom of the lingual, mesial and distal portions of the bridge member.

5. A prefabricated tooth comprising a prefabricated bridge member and having an incisal portion of the form of the tooth it is to replace, a lingual portion integral with the incisal portion, a mesial portion and a distal portion integral with the lingual portion and tapering to an approximate semicircle in form at the gingival, the lingual, mesial and distal portions having an inner surface, the lingual, mesial and distal portions having lingual, mesial and distal surfaces conforming to a natural tooth; and a prefabricated facial member having labial, mesial and distal faces conforming to a natural tooth, and the back face and sides conforming to the inner surfaces of the lingual, mesial and distal portions of the bridge member, and means carried by the prefabricated bridge member and the prefabricated facial member for retaining the parts together, the retaining means including a horizontal rib integral with the mesial, distal and lingual portions of the bridge member and extending straight across from the edges of the mesial and distal portions and a horizontal groove in the facial member corresponding with the rib.

6. A prefabricated tooth comprising a prefabricated bridge member and having an incisal portion of the form of the tooth it is to replace, a lingual portion integral with the incisal portion, a mesial portion and a distal portion integral with the lingual portion and tapering to an approximate semicircle in form at the gingival, the lingual, mesial and distal portions having an inner surface, the lingual, mesial and distal surfaces conforming to a natural tooth; and a prefabricated facial member having labial, mesial and distal faces conforming to a natural tooth, and the back face and sides conforming to the inner surfaces of the lingual, mesial and distal portions of the bridge member, and means carried by the prefabricated bridge member and the prefabricated facial member for retaining the parts together, in which a saddle is secured to the bottom of the lingual, mesial and distal portions of the

bridge member, and the retaining means for the bridge member is carried by the saddle.

7. A prefabricated facial member, to be used with a prefabricated bridge member having edges, comprising a prefabricated facial member having labial or buccal, mesial and distal surfaces corresponding to a natural tooth, a rear surface corresponding to the inner surface of a prefabricated bridge member including mesial and distal shoulders conforming to the edges of the bridge member, and recess means carried by the back of the member including a horizontal groove across the back of the member and inwardly to the shoulders and a vertical groove meeting the horizontal groove for retaining the facial member on a bridge member.

8. A prefabricated tooth as in claim 5 including a vertical rib integral with the lingual portions of the bridge member and integral with the horizontal rib, and a groove in the facial member corresponding with the second rib.

9. A prefabricated bridge member comprising a biting portion, a mesial portion and a distal portion integral with at least the lingual portion of the form of the tooth it is to replace, the lingual and distal portions having forward edges, a lingual portion integral with the biting portion, and approximately semicircular in form at least at the gingival, the lingual, mesial and distal portions having lingual, mesial and distal surfaces conforming to a natural tooth; at least the lingual, mesial and distal portions of the bridge member having inner surfaces, the lingual, mesial and distal portions having substantially uniform wall thickness, a horizontal rib integral with the lingual, mesial and distal portions and extending to the edge thereof, and a vertical rib integral with the lingual portion and the horizontal rib.
